UNITED STATES PATENT OFFICE

167,293

TOY TELEVISION CAMERA AND RADAR SCOPE

William T. Woodson, Manhattan Beach, and
Ralph Gallagher, Los Angeles, Calif.

Application September 11, 1951, Serial No. 16,604

Term of patent 7 years

(Cl. D34—15)

To all whom it may concern:

Be it known that we, William T. Woodson and Ralph Gallagher, both citizens of the United States, and residents, respectively, of the city of Manhattan Beach, in the county of Los Angeles and State of California, and of the city of Los Angeles, in the county of Los Angeles and State of California, have invented a new, original, and ornamental Design for a Toy Television Camera and Radar Scope, of which the following is a specification, reference being had to the accompanying drawing, forming a part thereof, in which:

Fig. 1 is a fragmentary perspective view of a toy television camera and radar scope, showing our new design;

Fig. 2 is a fragmentary side elevational view showing the side opposite Fig. 1;

Fig. 3 is a top plan view; and

Fig. 4 is an end elevational view showing the end opposite that shown in Fig. 1.

The dominant features of our design are shown in solid lines in the drawing.

We claim:

The ornamental design for a toy television camera and radar scope, as shown and described.

WILLIAM T. WOODSON.
RALPH GALLAGHER.
